UNITED STATES PATENT OFFICE.

DE FAY ZUMWALT, OF EL PASO, TEXAS.

WINDOW LOCK.

1,420,358.

Specification of Letters Patent. Patented June 20, 1922.

Application filed August 20, 1921. Serial No. 493,856.

To all whom it may concern:

Be it known that I, DE FAY ZUMWALT, a citizen of the United States, residing in the city of El Paso and State of Texas, 5 have invented new and useful Improvements in Window Locks, of which the following is a specification, reference being had to the accompanying drawings.

This invention is a window sash lock. 10 The object is to provide a simple and efficient lock of this kind, readily attachable to the sash, and affording a strong and easily operable safeguard against housebreakers.

In the drawings:

15 Figure 1 is a frontal elevation of a section of the upper sash with the device attached, and showing the catch raised so as to permit the lower sash to be raised.

20 Figure 2 is a similar view, but showing the catch lowered and braced to engage and lock the lower sash in its closed position.

Figure 3 is an edge view of the two sashes, showing how the lock on the upper sash engages the lower sash.

25 The invention consists of a holding strip of metal 1 fastened to the front face of one of the lower corners of the upper sash 2, and having its lower end 3 bent back at right angles to engage the under edge of 30 the sash 2. The sash is suitably mortised out at 11 to receive the strip 1, the end 3 thereof, and the other parts of the device, so as not to interfere with the raising of the lower sash 4 when desired. A catch

35 5 is hinged to the upper end of the holding strip 1 and adapted to open outwardly and down upon the top of the lower sash 4, and this catch is provided with teeth

6 for more effectually gripping and holding the lower sash. A brace 7 is hinged at 8 40 to the front of the upper sash 2 and has a finger 9 to engage an aperture 10 cut in the catch 5, as means for holding said catch in engagement with the sash 4. The lower sash 4 may be readily locked in closed position by lowering the catch 5 and bracing it with the brace 7, as just stated. To raise the sash 4, the brace 7 is removed from engagement with the catch 5, and the catch and brace are then folded back flatly into 45 the mortise 11.

While I have herein described a certain method of constructing and assembling the elements of my invention, it is understood same may be varied in minor details, not 55 departing from the spirit of my invention as defined in the appended claim.

I claim:

In combination with the upper and lower sash of a window, the upper sash being 60 suitably mortised to snugly receive the elements, a sash lock comprising a holding strip fastened to the front face of one of the lower corners of the upper sash, and having its lower end bent back at right 65 angles to engage the under edge of the said sash; a catch hinged to the upper end of the said holding strip and adapted to open out and down to engage the lower sash; and a brace hinged to the upper sash and adapt- 70 ed to engage the said catch to hold it in engagement with the lower sash.

DE FAY ZUMWALT.
